(57) **CLAIM**

The ornamental design for a suction lid with structural support, as shown and described.

DESCRIPTION

FIG. 1 is a top perspective view showing the front and top sides of the suction lid with structural support;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a perspective view of a second embodiment of the invention, all other views being substantially the same as FIGS. 2-7, the sole difference being the unitary lid region.
